UNITED STATES PATENT OFFICE

2,161,527

BLIND STITCH SEWING MACHINE

Charles W. Mueller, St. Louis, Mo., assignor to
 Lewis Invisible Stitch Machine Company, St.
 Louis, Mo., a corporation of Maine

Application June 19, 1937, Serial No. 149,258

17 Claims. (Cl. 112—178)

This invention relates to new and useful improvements in sewing machines generally, although more particularly to sewing machines of the blind stitch type.

In blind stitch sewing machines, such as is shown in each of my prior Patents 1,989,602, Jan. 29, 1935 and 2,018,186, Oct. 22, 1935, the reciprocatory ridge forming element is mounted directly below the needle on a work support which is fulcrumed on a horizontal pivot located in rear of the needle path. The ridge forming element which in one form is a disc, is provided with relatively low and high peripheral portions which are alternately positioned in cooperative relation with the needle to form resultant "anchor" and "skip" stitches. The driving connections between the main shaft and the oscillatory shaft which is journaled on the work support and which reciprocates the ridge forming element, is such that when a seam or extremely thick layers of fabrics are fed over the element, the work support will be depressed and the driving connections will cause the oscillatory shaft to rock and thereby shift the ridge forming element out of its true cooperative relation with the needle with the result that one or more stitches will be improperly positioned in the fabric or fabrics.

One of the important objects of this invention is to provide driving connections between the main shaft and the reciprocatory ridge forming element operating shaft whereby the element will remain in its true cooperative relation with the needle when the pivoted work support is depressed and thereby insure the proper positioning of the stitches in the fabric or fabrics.

Another object of the invention is to provide a main frame which includes a standard, a laterally extending upper arm and a forwardly and downwardly inclined arm, a reciprocatory needle and a presser foot mounted on the front end of the forwardly extending arm, and a work support which is fulcrumed on a horizontal pivot located in front of the needle path, whereby the presser foot will remain at the same height relative to the operator and yet afford increased room under the laterally extending arm for the passage of work when the work is being fed rearwardly and also when the work is being removed from the machine upon depression of the pivoted work support.

A further object of the invention is to provide a work clamp which cooperates with the presser foot and which comprises two independently mounted sections which are spring pressed up-

wardly for alternate cooperation with a top feed dog and the presser foot, together with means for varying the relative pressures of the sections against the foot, whereby a body fabric and an overlying hem fold may be fed properly.

A still further object of the invention is to provide a folder support which is mounted on the main frame in front of the work support to swing about a vertical pivot whenever it is desired to shift the folder support out of operative position and to provide means for elevating the same during said swinging movement to insure the folder clearing the upper surface of the work support.

With these and other objects in view which will more fully appear, the nature of the invention will be more clearly understood by following the description, the appended claims, and the several views illustrated in the accompanying drawings.

In the drawings:

Figure 1 is a top plan view of a machine constructed in accordance with my invention,

Figure 2 is a right hand elevation thereof, the standard being shown in section,

Figure 3 is a front elevation thereof, the folder being omitted,

Figure 4 is a left end elevation thereof,

Figure 5 is a bottom plan view of the machine,

Figure 6 is an enlarged fragmentary vertical section taken through the base and work support substantially in the plane of oscillation of the needle,

Figure 7 is an enlarged detail section showing a slight depression of the work support relative to the needle,

Figure 8 is an enlarged vertical section showing the work support in its locked or normal position,

Figure 9 is a similar view but showing the work support in its unlocked or fully depressed position,

Figure 10 is a view showing the driving connections between the main shaft and the oscillatory shaft which operates the ridge forming element, the view indicating the limits of the oscillatory movements of the element when forming all "anchor" stitches,

Figure 10^a is a view showing the corresponding position of the control lever,

Figure 11 is a view similar to Figure 10 but showing the limits of oscillatory movements of the element when forming alternate "anchor" and "skip" stitches,

Figure 11^a is a view showing the corresponding position of the control lever,

Figure 12 is a detail side elevation, partly in

section, showing the adjustable tensioning means for a work clamp section,

Figure 13 is a perspective view of a portion of the main frame showing the post which supports the work support,

Figure 14 is a perspective view of the left end of the work support,

Figure 15 is a vertical section taken through the pivot of the folder support,

Figure 16 is a plan view of the presser foot and showing the needle, the top feed dog, the ridge forming element, and the work clamp, and

Figure 17 is a top plan view of the left end of the work support showing the ridge forming element, the operating shaft therefor, and the work clamp.

Like reference numerals designate corresponding parts throughout the several figures of the drawings.

The sewing machine includes a main frame A which comprises a base 5, a standard 6, an arm 7 which extends laterally from the upper end of the standard and terminates in a forwardly extending arm 8 which is inclined downwardly and forwardly relative to the base, and a post 9 which is integral with the base and is located at the front thereof and at the right of the arm 8, the post being inclined forwardly and having its upper portion disposed in a vertical plane in front of the front end of the arm 8 and in a horizontal plane below said front end of said arm.

Rigidly fixed to the forward or free end of the arm 8, is a horizontal presser foot B having a centrally located longitudinal opening or slot 10 formed therein, the foot being forwardly and downwardly inclined in a plane disposed in parallelism to the major axis of said arm 8.

Journaled in the upper end of the standard 6 and in the arm 7 is a main shaft 11, and journaled in the arm 8 and extending longitudinally thereof is an oscillatory needle shaft 12 having a needle arm 13 fixed to its front end. The needle shaft 12 is located directly above the presser foot opening 10 and has its longitudinal axis in a downwardly and forwardly inclined plane disposed in parallelism with the presser foot. Attached to the needle arm 13 is a curved needle 14 which reciprocates across the opening 10 of the foot. The needle shaft 12 is oscillated from the main shaft 11 by connections such as is shown in my prior Patent 2,018,186 referred to above. A looper or spreader 15 cooperates with the needle 14 in the usual manner to form single thread chain stitches, although any other type of complementary stitch forming mechanism may be employed if desired. The looper 15 is fixed to a looper rod 16 which is fulcrumed on a depending arm 17 pivoted on a horizontal pin 18 mounted in the arm 8 and the looper rod is driven from the main shaft 11 by the usual connections.

A work support C is clamped by screws 19 to a horizontal pivot shaft 20 journaled in spaced bearings 21, 21 formed in the post 9 of the main frame. It will be noted that the pivot shaft 20 is disposed in a plane parallel to the main shaft 11 and that said pivot shaft is located considerably in front of the needle 14 as well as in front of the presser foot B. This work support C has its left end reduced to form a horn 22 and projecting laterally from the outer end of the horn is a rectangular frame 23 having an open top and bottom. This frame 23 is located directly under the presser foot B and includes front and rear walls 24, 25 and an end wall 26.

Operating in the presser foot opening 10 for intermittently projecting a node of fabric upwardly into needle penetrating position, is a ridge forming element D which in this instance consists of a disc fixed to an operating shaft 27 which is journaled at the end in screw bearings 28, 29, the screw bearing 28 being mounted in an opening 30 formed in the end wall 26 of the frame 23 and the screw bearing 29 being mounted in an opening 31 formed in a lug 32 which depends from the under side of the work support C. The oscillatory operating shaft 27 is disposed in a horizontal plane in parallelism not only with the main shaft 11 but also with the pivot shaft 20 of the work support. It will, therefore, be seen that the work support C extends rearwardly from the pivot shaft 20 to a point under the presser foot B and that this work support is capable of swinging downwardly away from the presser foot or upwardly toward the same. It will also be observed that the shaft 27 which operates the ridge forming element D is disposed in rear of the pivot shaft 20 and is movable upwardly and downwardly with the work support and consequently when the work support is lowered the ridge forming element D will be correspondingly lowered with respect to the path of the needle. The ridge-forming disc D is formed with a concentric periphery 33 and with a radial front edge 34, and a recess 35 is formed at their juncture, the recess forming a resultant step 36. It will be observed that the concentric edge 33 and the step 36 form peripheral surfaces or portions of different radii which are arranged in tandem, the portion 33 constituting a high portion and the step 36 constituting a low portion. When the high portion 33 is positioned under the needle the latter will form resultant "anchor" stitches in the fabric or fabrics and when the low portion 36 is positioned below the needle, the latter will form "skip" stitches in the fabric or fabrics. In other words, the effective depth of needle penetration in the fabric or fabrics is constant when the high portion 33 is positioned below the needle but when the low portion 36 is positioned below the needle the depth of needle penetration will be decreased, as fully explained in my prior Patent 2,018,186 referred to above.

An upwardly spring pressed work clamp E is mounted on the work support C for alternate cooperation with presser foot B and a 4-motion top feed dog F. The top feed dog F operates in the opening 10 of the presser foot B and is supported on the frame arm 8 and is operatively connected to the main shaft 11 in the usual manner. This feed dog operates in rear of the needle path and cooperates with the work clamp E to intermittently feed the fabric rearwardly when the needle is out of said fabric. The work clamp E cooperates with the bottom of the foot B to clamp the fabric therebetween during the idle motions of the feed dog F whereby said fabric will be held against the thrusts of the needle.

The work clamp E includes two separate clamping sections 37, 37 which are disposed side by side and extend longitudinally of the presser foot from a point in front of the needle path to a point well in rear thereof, the front portions of the sections being recessed to receive the ridge forming disc D and the rear portions of said sections being disposed in close relation below the presser foot opening 10 whereby the feed dog F will cooperate with both sections. The work clamp sections 37 are each pivoted as

at 38 on the free end of a horizontal arm 39 of a bell crank lever 40, the other arm 41 of the lever projecting downwardly in front of the front wall 24 of the rectangular frame 23 of the work support. These two levers 40 are arranged side by side and are fulcrumed at their angles on a common pivot shaft 41^a which is disposed in parallelism with the disc operating shaft 27 and is mounted in a bearing opening 42 formed in the horn 22 of the work support and secured therein by a set screw 43. Associated with the vertical arm 41 of each lever is a coil spring 44, said spring extending through an opening 45 formed in the front wall 24 of said frame 23, the front end of the spring being connected to the lever arm 41 and the rear end of the spring being connected to an adjustable tension screw 46 mounted in the rear wall 25 of said frame 23. These two springs 44 function to yieldably urge the clamping sections 37 upwardly against the presser foot B or top feed dog F. Adjustable stop screws 47, 47 have threadable engagements in openings 48, 48 formed in the front wall 24 of the frame 23 directly above the openings 45 for cooperation with the vertical arms 41, 41 of the bell crank levers 40, 40 and to thereby independently and variably limit the upward movement of the clamping sections 37, 37. These independent stops 47, 47 are very important in hemming operations. For instance, in hemming the bottom of a circular-cut skirt, there is considerable fullness in the hem fold, and this fullness must be gathered in while the work is being fed through the machine. If there is too much spring pressure applied to the right hand clamping section 37 which engages the fabric directly below the hem fold, it becomes very difficult for the operator to retard the base layer slightly in order to allow the top feed to fill or gather in the surplus material. Therefore, by providing the independently adjustable stops 47, 47 the pressure on the clamping sections 37, 37 may be adjusted to suit working conditions. Furthermore, sometimes the above condition is reversed and a lesser pressure on the left hand clamping section 37 will be desirable.

The work support C is capable normally of a small free vertical movement about its pivot 20 to permit not only a variation in the thicknesses of materials being stitched but also to permit seams being fed over the ridge forming disc D. To this end, the work support C is provided with depending integral front and rear walls 49, 50 respectively arranged on opposite sides of the disc operating shaft 27. A head 51 includes a horizontal attaching plate 52 and a depending tubular neck 53 having an open lower end. The head 51 is rigidly attached to the lower edges of the depending walls 49, 50 by screws 54, 54. Mounted in said neck for vertical movements relative thereto is a core or support 55. A limiting screw 56 passes downwardly through a non-threaded opening 57 formed in the plate 52, the lower end of the screw being threaded into the core 55 and the head 58 of said screw cooperating with the plate 52 to limit the upward movement of the work support C relative to the core 55. The upper surface of the core is normally spaced below the plate 52 and the upper portion of the core is reduced to form a resultant peripheral recess for receiving a coil spring 59 which engages the bottom wall of the recess and the plate 52 and functions to yieldably retain the work support C against downward movement relative to said core.

The core 55 is normally locked against vertical movements, but when the core is moved vertically the work support C, the disc D, and the work clamp E are moved with it. The lower end of the core 55 is provided with a depending lug 5. A toggle is connected to the lug 60 and to the base 5 of the main frame. The toggle includes a bell crank lever 61 which includes an upright arm 62 and a forwardly extending horizontal arm 63. The lower end of the arm 62 is fulcrumed on an eccentric 64 which is fixed to a horizontal shaft 65, the latter being disposed below the disc operating shaft 27 and in generally vertical alinement with said shaft 27 and with the needle. The ends of the shaft 65 are journaled in the base 5 below the upper surface thereof. A normally uprightly disposed link 66 is pivotally connected at its upper end by a pin 67 to the lug 60 and at its lower end by a pin 68 to the upper end of the toggle arm 62, the pin 68 being rigidly secured to the link 66 by a set screw 69. A coil spring 70 is disposed around the projecting end of the pin 68, one end of the spring being anchored in a transverse slot 71 formed in the outer end of the pin and the other end of the spring engaging under a stop pin 72 fixed to the link 66. The spring 70 functions to yieldably retain the toggle elements 62, 66 in their longitudinally aligned or locked positions, as shown in Figure 8, and a stop shoulder 73 fixed to the arm 62 cooperates with the stop shoulder 74 on the bottom of the link 66 in the manner illustrated in Figure 8 to prevent the toggle elements passing beyond their locked positions. It will be noted that the arm 62 and the link 66, when in their normal or locked positions, are in generally vertical or upright alinement, i. e., the pivots 61, 71 and 65 are in alinement in a plane which is slightly inclined to the vertical, or in other words, in a plane at right angles to the plane of the foot B. A chain 75 which is adapted to be connected to a treadle or knee-press, has its upper end connected to the forward end of the horizontal arm 63 of said bell crank lever. Thus upon operation of the knee-press or treadle the toggle will be broken and the support or core 55 together with the work support C and parts mounted thereon, will be depressed to permit the ready insertion or withdrawal of the material, and upon release of said knee-press or treadle, the parts will be returned to their normal position by the spring 70. It will, therefore, be seen that when the toggle is in its locked or normal position, the work support C is capable of having a slight vertical movement against the tension of the spring 59 so as to permit various thicknesses of fabrics and seams being fed through the machine.

In order to positively adjust the normal vertical position of the work support C together with the disc D, and thereby set the machine for materials of different thicknesses, I have provided a hand adjusting shaft 76 which is journaled in a bushing 77 mounted in a tubular bearing bracket 78 secured in an opening formed in the front wall of the standard 6. A finger knob 79 is rigidly attached to the front end of the shaft 76 and a spring pressed pin 80 cooperates with the knob to retain the shaft in any position of adjustment. Journaled on the bracket 78 is a worm wheel 81 which is in constant mesh with a worm 82 formed on the inner end of the shaft 76. Journaled in the base 5 is a horizontal rock shaft 83 having a rock arm 84 fixed to its right hand end, said arm being pivotally connected by a link 85 to the worm gear 81. The other end of

the rock shaft 83 is provided with a rock arm 86 which is pivotally connected to the rear end of a rack bar 87 which extends forwardly along the base to a point below and in front of the eccentric carrying shaft 65. The rack bar 87 is provided along its upper forward edge with rack teeth 88 which engage the teeth of a pinion 89 fixed on said shaft 65. A disc 90 is journaled on the shaft 65 and is provided with a pin 91 forming a support for the front end of said rack bar. A coil spring 92 is connected at one end to the disc 90 and at its other end to the base 5 and functions to urge the pin 91 upwardly whereby the rack bar will be retained yieldably in engagement with the pinion 89. If desired, a coil spring 92a may be provided and attached to the base 5 and the bar 87 as shown in Figure 5 so as to be effective to constantly urge the bar forwardly. It will, therefore, be seen that when the knob 79 is rotated the rack bar 87 will be moved endwise, the shaft 65 together with the eccentric 64 will be rotated, and the work support will be raised or lowered, depending on the direction of rotation of the knob.

25 The ridge forming element D is reciprocated from the main shaft 11 by a train of mechanism including a manual control lever whereby either the high or low portions 33, 36 of the disc or element will be alternately presented to the needle to thereby form alternate "anchor" and "skip" stitches in the material or whereby the high portion 33 only of the disc or element will be successively presented to the needle to thereby form successive "anchor" stitches in the material. To this end, a bell crank lever 93 is journaled on a horizontal axis 94 in the standard 6 and below the main shaft 11. The bell crank lever 93 includes a forwardly extending horizontal arm 95 which is connected by a link 97 to the main shaft 11 through the medium of a 2-to-1 reduction gear coupling which is indicated as a whole by the numeral 98 and which is fully shown and described in my prior Patent 1,989,602 referred to above. The bell crank lever 93 includes a depending vertical arm 99 which is pivotally connected as at 100 to the rear end of a forwardly extending link 101. A horizontal shaft 102 is journaled in a base lug 103 at a point between the pivot shaft 20 of the work support C and the disc operating shaft 27, said shaft 102 being disposed in parallelism with said shafts 20 and 27. Fixed to the right hand end of the shaft 102 is an eccentric pin 104 and a lever 105 is journaled intermediate its ends on said eccentric pin. The lower arm 106 of said lever is pivotally connected as at 107 to the forward end of the link 101 and the upper arm 108 of said lever is pivotally connected as at 109 to a rearwardly extending link 110 which is pivotally connected at its rear end as at 111 to a depending rock arm 112 clamped to the disc operating shaft 27. Fixed to the left hand end of the eccentric shaft 102 is an upwardly extending rock arm 113 and pivotally connected to the upper end 65 of said arm as at 114 is a rearwardly extending link 115, the rear end of said link being pivotally connected as at 116 to the lower end of a manually operable control lever 117 which is fulcrumed on the disc operating shaft 27 and has its upper end 70 provided with a finger-piece or knob 118 which projects through an opening 119 formed in the work support C. The knob 118 also projects upwardly through a slot 120 formed in a plate 121 mounted on the upper surface of the work support C.

It will be noted that the eccentric pin 104 constitutes a shiftable fulcrum for the lever 105 and that when the shaft 102 is oscillated by the manually control lever 117 said fulcrum will be shifted either forwardly or rearwardly and the disc operating shaft 27 will be angularly shifted thereby, and consequently the disc D will be shifted angularly with respect to the needle path. The driving connections between the main shaft 11 and the disc operating shaft 27 are such that the disc D will partake of a greater angular movement during alternate rearward strokes thereof and a lesser angular movement during intermediate rearward strokes. Thus when the manually control lever 117 is in the position shown in Figure 10a the high peripheral portion 33 of the disc D will be presented to the needle during successive rearward movements of the disc whereby successive "anchor" stitches will be formed in the fabric; and when the control lever is in the position shown in Figure 11a the high and low peripheral portions 33, 36 will be alternately presented to the needle whereby alternate "anchor" and "skip" stitches will be formed in the fabric. It will furthermore be observed that when the work support C is in its normal or locked position said support is capable of having a slight downward movement due to the intermediate spring 59, and that by reason of the lever 105 being disposed between the pivot shaft 20 of the work support and the disc operating lever 27 together with the link 110 which connects the lever 105 with the rock arm 112, this slight downward movement of the work support will maintain the low peripheral portion 36 of the disc D in proper cooperative relation to the needle path whenever said low portion 36 is positioned in cooperative relation with the needle and consequently the stitches will be properly positioned in the fabric.

As previously stated this machine is particularly adapted for blind stitching hems and therefore I have provided a support G for an adjustable hemmer H. The support G is mounted on the base 5 in front of the work support C and is adapted to swing about a vertical pivot whenever it is desired to dispense with the folder. The support G is provided at its right hand end with a depending bearing lug 122 having a hardened plate 123 attached to its lower end. A forwardly extending bracket arm 124 is attached to the front edge of the base 5 and is provided at its front end with a vertical bore or socket 125 in which is mounted the lower end of a tubular hinge pin 126, said pin being rigidly secured to the bracket arm 124 by set screws 127. The hinge pin 126 projects upwardly into a vertical bore or bearing opening 128 formed in the bearing lug 122. A stop collar 129 is clamped to the hinge pin 126 at a point between the bracket 124 and the bearing lug 122. The hinge pin 126 is provided with upper and lower flanged caps 130, 131 which respectively engage the support G and the bracket 124, and a coil spring 132 is disposed within the pin and has its ends connected to said caps for yieldably retaining the folder support G against the stop collar 129. The upper surface of the folder support G is disposed below the forward end of the presser foot B in order to properly position the folder, and consequently the upper surface of the support G is disposed in a horizontal plane below the upper surface of the work support C. The hemmer H includes a base 133 which is attached to the folder support G by screws 134. The left hand section 135 of

the folder is laterally adjustable and includes an arm 136 which is shiftable in guides 137, 137 mounted on the base 133, said arm being disposed in parallelism with the disc operating shaft 27. Furthermore, the arm 136 is disposed in a horizontal plane below the upper surface of the work support C as shown in Figure 2, and consequently means are provided for automatically elevating the folder support G when the latter is swung forwardly whereby the right hand end of the arm 136 will be elevated a sufficient distance to clear the upper surface of the work clamp C. To this end, the stop collar 129 is provided with a cam 138 and the plate 123 which is attached to the bearing lug 122 is provided with a depending cam follower 139 which cooperates with the cam 138 to effect an elevation of the folder support G against the tension of the spring 132. A notch or seat 140 is formed in the upper surface of the stop collar 129 for receiving the cam follower 139 when the folder support G is swung to its inoperative or forward position and thereby frictionally retain said support against accidental swinging movement.

It is of course to be understood that the details of structure and arrangement of parts may be variously changed and modified without departing from the spirit and scope of my invention.

I claim:

1. In a blind stitch sewing machine, the combination with a main frame including a base and a forwardly extending arm disposed in a plane above the base, of a main shaft journaled in the frame, a presser foot fixed to the front end of the arm and provided with an opening, a stitch forming mechanism mounted on the arm and including a needle mounted for reciprocations above the foot and across the opening therein, a horizontal work support mounted on the base to swing upwardly and downwardly relative to the foot and about a horizontal axis located in front of the needle, means for normally retaining the work support yieldably against depression, a reciprocatory ridge forming element operating in the presser foot opening for projecting a ridge of fabric upwardly into needle penetrating position and movable upwardly and downwardly with said work support, an oscillatory shaft journaled on the work support and disposed in parallelism with the axis thereof and operatively connected to said element, and driving connections between the main and oscillatory shafts for operating the latter and including devices for retaining the oscillatory shaft against angular movement upon depression of the work support.

2. In a blind stitch sewing machine, the combination with a main frame including a base and a forwardly extending arm disposed in a plane above the base, of a main shaft journaled in the frame, a presser foot fixed to the front end of the arm and provided with an opening, a stitch forming mechanism mounted on the arm and including a needle mounted for reciprocations above the foot and across the opening therein, a horizontal work support mounted on the base to swing upwardly and downwardly relative to the foot and about a horizontal axis located in front of the needle, means for normally retaining the work support yieldably against depression, an oscillatory ridge forming disc operating in the presser foot opening for projecting a ridge of fabric upwardly into needle penetrating position and movable upwardly and downwardly with said work support, an oscillatory shaft journaled on

the work support and disposed in parallelism with the axis thereof and rigidly connected to said disc, and driving connections between the main and oscillatory shafts for operating the latter and including devices for retaining the oscillatory shaft against angular movement upon depression of the work support.

3. In a blind stitch sewing machine, the combination with a main frame including a base and a forwardly extending arm disposed in a plane above the base, of a main shaft journaled in the frame, a presser foot fixed to the front end of the arm and provided with an opening, a stitch forming mechanism mounted on the arm and including a needle mounted for reciprocations above the foot and across the opening therein, a horizontal work support mounted on the base to swing upwardly and downwardly relative to the foot and about a horizontal axis located in front of the needle, means for normally retaining the work support yieldably against depression, an oscillatory ridge forming disc operating in the presser foot opening for projecting a ridge of fabric upwardly into needle penetrating position and movable upwardly and downwardly with said work support, said disc having high and low peripheral work presenting portions arranged in tandem, an oscillatory shaft journaled on the work support and disposed in parallelism with the axis thereof and rigidly connected to said disc, and driving connections between the main and oscillatory shafts for operating the latter and including devices for retaining the oscillatory shaft against angular movement upon depression of the work support, said driving connections periodically presenting to the needle first one of said disc portions and then the other to thereby vary the effective depths of the needle penetrations.

4. In a blind stitch sewing machine, the combination with a main frame including a base and a forwardly extending arm disposed in a plane above the base, of a main shaft journaled in the frame, a presser foot fixed to the front end of the arm and provided with an opening, a stitch forming mechanism mounted on the arm and including a needle mounted for reciprocations above the foot and across the opening therein, a horizontal work support mounted on the base to swing upwardly and downwardly relative to the foot and about a horizontal axis located in front of the needle, means for normally retaining the work support yieldably against depression, a reciprocatory ridge forming element operating in the presser foot opening for projecting a ridge of fabric upwardly into needle penetrating position and movable upwardly and downwardly with said work support, an oscillatory shaft journaled on the work support and disposed in parallelism with the axis thereof and operatively connected to said element, and driving connections between the main and oscillatory shafts for operating the latter and including devices for retaining the oscillatory shaft against angular movement upon depression of the work support, said devices including a substantially vertical lever fulcrumed on a horizontal axis located intermediate the work support pivot and the oscillatory shaft, a rock arm fixed to the oscillatory shaft, and a link connecting the upper end of the lever and the rock arm.

5. In a blind stitch sewing machine, the combination with a main frame including a base and a forwardly extending arm disposed in a plane above the base, of a main shaft journaled in

the frame, a presser foot fixed to the front end of the arm and provided with an opening, a stitch forming mechanism mounted on the arm and including a needle mounted for reciprocations above the foot and across the opening therein, a horizontal work support mounted on the base to swing upwardly and downwardly relative to the foot and about a horizontal axis located in front of the needle, means for normally retaining the work support yieldably against depression, an oscillatory ridge forming disc operating in the presser foot opening for projecting a ridge of fabric upwardly into needle penetrating position and movable upwardly and downwardly with said work support, an oscillatory shaft journaled on the work support and disposed in parallelism with the axis thereof and rigidly connected to said disc, and driving connections between the main and oscillatory shafts for operating the latter and including devices for retaining the oscillatory shaft against angular movement upon depression of the work support, said devices including a substantially vertical lever fulcrumed on a horizontal axis located intermediate the work support pivot and the oscillatory shaft, a rock arm fixed to the oscillatory shaft, and a link connecting the upper end of the lever and the rock arm.

6. In a blind stitch sewing machine, the combination with a main frame including a base and a forwardly extending arm disposed in a plane above the base, of a main shaft journaled in the frame, a presser foot fixed to the front end of the arm and provided with an opening, a stitch forming mechanism mounted on the arm and including a needle mounted for reciprocations above the foot and across the opening therein, a horizontal work support mounted on the base to swing upwardly and downwardly relative to the foot and about a horizontal axis located in front of the needle, means for normally retaining the work support yieldably against depression, an oscillatory ridge forming disc operating in the presser foot opening for projecting a ridge of fabric upwardly into needle penetrating position and movable upwardly and downwardly with said work support, said disc having high and low peripheral work presenting portions arranged in tandem, an oscillatory shaft journaled on the work support and disposed in parallelism with the axis thereof and rigidly connected to said disc, and driving connections between the main and oscillatory shafts for operating the latter and including devices for retaining the oscillatory shaft against angular movement upon depression of the work support, said driving connections periodically presenting to the needle first one of said disc portions and then the other to thereby vary the effective depths of the needle penetrations, said devices including a substantially vertical lever fulcrumed on a horizontal axis located intermediate the work support pivot and the oscillatory shaft, a rock arm fixed to the oscillatory shaft, and a link connecting the upper end of the lever and the rock arm.

7. In a blind stitch sewing machine, the combination with a horizontal presser foot having an opening, an intermittent top feed dog operating in said opening, separate work clamp sections located below the foot for alternate cooperation with the feed dog and the foot, separate spring means for pressing said clamp sections upwardly into said cooperative relation with said feed dog and foot, and means for varying the pressure of one of said spring means.

8. In a blind stitch sewing machine, the combination with a horizontal presser foot having an opening, an intermittent top feed dog operating in said opening, separate work clamp sections located below the foot for alternate cooperation with the feed dog and the foot, separate spring means for pressing said clamp sections upwardly into said cooperative relation with said feed dog and foot, and separate means for varying independently the pressures of said 10 separate spring means.

9. In a blind stitch sewing machine, the combination with a horizontal presser foot having an opening, an intermittent top feed dog operating in said opening, a support located below the foot, separate work clamp sections mounted on the support for alternate cooperation with the feed dog and the foot, springs respectively interposed between said sections and the support for pressing said sections upwardly into said 15 cooperative relation with said feed dog and foot, and means located between the support and one of said sections for varying the pressure of the 20 associated spring.

10. In a blind stitch sewing machine, the combination with a horizontal presser foot having an opening, an intermittent top feed dog operating in said opening, a support located below the foot, separate work clamp sections mounted on the support for alternate cooperation with the feed dog and the foot, springs respectively interposed between said sections and the support for pressing said sections upwardly into said 30 cooperative relation with said feed dog and foot, and separate means located between the support and the sections for varying independently 35 the pressures of the associated springs.

11. In a blind stitch sewing machine, the combination with a horizontal presser foot having an opening, an intermittent top feed dog operating in said opening, a support located below the foot, separate bell crank levers fulcrumed on the support to swing about a horizontal axis, each lever including a horizontal arm and a depending vertical arm, work clamp sections respectively pivoted on the horizontal arms for alternate cooperation with the feed dog and the foot, coil springs respectively connecting the vertical arms of the levers and the support for pressing said sections upwardly into said cooperative relation with said feed dog and foot, and a stop screw threadably mounted in the support for engagement by the vertical arm of one lever to variably limit the pressure of the associated spring.

12. In a blind stitch sewing machine, the combination with a horizontal presser foot having an opening, an intermittent top feed dog operating in said opening, a support located below the foot, separate bell crank levers fulcrumed on the support to swing about a horizontal axis, each lever including a horizontal arm and a depending vertical arm, work clamp sections respectively pivoted on the horizontal arms for alternate cooperation with the feed dog and the foot, coil springs respectively connecting the vertical arms of the levers and the support for pressing said sections upwardly into said cooperative relation with said feed dog and foot, and stop screws threadably mounted in the support for engagements by the vertical arms of said levers to variably and independently limit the pressures of the associated springs.

13. In a sewing machine, the combination with a base and a laterally extending arm, of a presser

foot mounted on the free end of said arm, a reciprocating needle supported on the arm above the foot, a work support mounted on the base and having a portion underlying the foot, a folder support located in front of the work support and mounted on a vertical axis to swing forwardly from an operative position to an inoperative position, and a folder mounted on said folder support for directing a folded fabric to the 10 needle when said support is in its operative position.

14. In a sewing machine, the combination with a base and a laterally extending arm, of a presser foot mounted on the free end of said arm, a reciprocating needle supported on the arm above the foot, a work support mounted on the base and having a portion underlying the foot, a folder support located in front of the work support and mounted on a vertical axis to swing forwardly 15 from an operative position to an inoperative position, the upper surface of the folder support being normally disposed in a lower horizontal plane than the upper surface of the work support, and a folder mounted on said folder support for directing a folded fabric to the needle when said support is in its operative position, a cam follower fixed to the folder support for cooperation with said cam whereby the folder support will be elevated and the folder will clear the work support when the 20 folder support is swung to its inoperative position, and spring means between the post and the folder support for yieldably retaining the cam follower in engagement with the cam.

25

15. In a sewing machine, the combination with a base and a laterally extending arm, of a presser foot mounted on the free end of said arm, a reciprocating needle supported on the arm above the foot, a work support mounted on the base and having a portion underlying the foot, a post 30 mounted on the base in front of the work support, a bearing collar fixed to the post and provided with a cam, a folder support mounted on said post to swing forwardly from an operative position to an inoperative position, the upper surface of the folder support being normally disposed in a lower horizontal plane than the upper 35 surface of the work support, a folder mounted on said folder support for directing a folded fabric to the needle when said support is in its operative position, and a cam follower fixed to the folder support for cooperation with said cam whereby the folder support will be elevated and the folder will clear the work support when the 40 folder support is swung to its inoperative position, said collar being provided with a notch for receiving the cam follower to retain the folder support in its inoperative position.

16. In a sewing machine, the combination with a base and a laterally extending arm, of a presser foot mounted on the free end of said arm, a reciprocating needle supported on the arm above the foot, a work support mounted on the base and having a portion underlying the foot, a post 5 mounted on the base in front of the work support, a bearing collar fixed to the post and provided with a cam, a folder support mounted on said post to swing forwardly from an operative position to an inoperative position, the upper surface of the folder support being normally disposed in a lower horizontal plane than the upper surface of the work support, a folder mounted 10 on said folder support for directing a folded fabric to the needle when said support is in its operative position, a cam follower fixed to the folder support for cooperation with said cam whereby the folder support will be elevated and the folder will clear the work support when the 15 folder support is swung to its inoperative position, and spring means between the post and the folder support for yieldably retaining the cam follower in engagement with the cam.

17. In a sewing machine, the combination with a base and a laterally extending arm, of a presser foot mounted on the free end of said arm, a reciprocating needle supported on the arm above the foot, a work support mounted on the base and having a portion underlying the foot, a post 20 mounted on the base in front of the work support, a bearing collar fixed to the post and provided with a cam, a folder support mounted on said post to swing forwardly from an operative position to an inoperative position, the upper 25 surface of the folder support being normally disposed in a lower horizontal plane than the upper surface of the work support, a folder mounted on said folder support for directing a folded fabric to the needle when said support is in its operative position, and a cam follower fixed to the folder support for cooperation with said cam whereby the folder support will be elevated and the folder will clear the work support when the 30 folder support is swung to its inoperative position, and spring means between the post and the folder support for yieldably retaining the cam follower in engagement with the cam.
